UNITED STATES PATENT OFFICE.

ROBERT W. GILLESPIE, OF ST. LOUIS, MISSOURI.

SEAL-LOCK.

SPECIFICATION forming part of Letters Patent No. 409,084, dated August 13, 1889.

Application filed August 1, 1888. Serial No. 281,619. (No model.)

To all whom it may concern:

Be it known that I, ROBERT W. GILLESPIE, of the city of St. Louis, in the State of Missouri, have invented a certain new and useful Improvement in Self-Fastening Seal-Locks, of which the following is a full, clear, and exact description, reference being had to the accompanying drawings, forming part of this specification.

10 This invention relates to devices for sealing cars with a frangible seal that cannot be tampered with without breakage; and the invention consists in features of novelty hereinafter fully described, and pointed out in 15 the claims.

Figure I is a detail elevation of a car with my seal attached. Fig. II is a front view of the lock and shows its thimble-seal in section, and part of one locking-barb broken 20 away to show its clutch-hold within the locking-chamber of the thimble-seal; and Fig. III is a horizontal section taken on line III III, Fig. II, and shows the barbs of the locking-pin seated within the locking-chamber of the 25 thimble-seal.

Referring to the drawings, in which similar figures of reference indicate like parts in all the views, 1 represents the side of a car to which my lock is attached. 2 is the door, and 30 3 the door-jamb to which the door is locked.

4 is a hasp, which may be secured by a staple, or by any other suitable means, to the door.

5 is a staple seated in the door-jamb, on 35 which the slot 6 of the hasp engages when it is desired to fasten the door.

7 represents a U-shaped locking pin or key, which is preferably made of steel, and 8 is a ring-head which surmounts one end of said 40 locking-pin, and is formed integral therewith to prevent its dropping through its seat in the staple.

9 represents the forks of the bifurcated point of the locking-pin, and 10 are pointed 45 barbed heads that surmount the forks.

11 represents a frangible thimble-seal, which is preferably made of pottery, and may be either glazed or not; but it may be of glass or any other suitable material.

50 12 is the key-hole for the entrance of the locking-pin within said seal, and 13 is the

locking-chamber at the terminal of the opening in the thimble and into which the key-hole leads. The said locking-chamber is of larger diameter than the key-hole, and at its 55 junction therewith the enlargement causes a shoulder 14, which is beveled downward outwardly from the key-hole, so as to form a barbed clutch-hold in which the hook of the barbed heads of the locking-pin are seated 60 when the car is locked.

15 represents a collar around the locking-pin a short distance below its forks, and 16 is an annular recess at the entrance to the key-hole of the thimble-seal, in which said collar 65 is seated when the lock is sealed, the same making an anti-picker device.

It will be seen that by this last provision it would be impossible to pick the lock, for neither a wire or any other picker could be 70 projected through the sharp angled turns between said collar and its seat. Neither is there room for the insertion of any kind of picker.

The manner of attachment and operation 75 of the lock is as follows: The car-door being closed, the hasp that is secured to said door is seated on the staple that is secured to the door-jamb, and the bifurcated end of the U-shaped locking-pin is passed through said 80 staple and turned around until its ring-head is seated on the staple. The barbed points of the bifurcated end of the locking-pin will then point upward, and are inserted in the key-hole of the thimble-seal, and said barbed 85 points are passed up through said key-hole into the locking-chamber that surmounts the key-hole. The spring-forks of the locking-pin are compressed together as they enter the key-hole and spring out again when they enter the locking-chamber, which is of enlarged 90 diameter to that of the key-hole. The projected barbs on the points of the locking-pin then seat themselves and clutch onto the bevel-shoulder around the junction of the 95 key-hole to the locking-chamber. After the seal-lock is thus secured it is impossible for either an unauthorized or authorized party to tamper with it or unlock it without breaking the frangible thimble-seal, which may be 100 made of very cheap construction of pottery or other material. Nearly the whole cost of

the device, which in itself is small, is in the |
spring locking-pin, which is virtually inde-
structible.

As there is no means by which any one can
5 obtain entrance to the car without breaking
the frangible thimble-seal, it is evident that
if said entrance is effected the broken thim-
ble would be a certain tell-tale of said trespass.

The **U** shape of the locking-pin provides
10 the presentation of the forks of the locking-
pin upward in a vertical or nearly vertical di-
rection, so that the entrance to the key-hole
of the thimble-seal, when seated on said pin,
may be protected from the entrance of water.
15 This is an important feature of the device, for
it avoids the freezing up and consequent
breakage of the seals, which has been a mat-
ter of very frequent occurrence in frosty
weather.

20 In case of the unintentional breakage of the
thimble-seal from a collision or other unusual
accident, and it is desired to fasten the locking-
pin in its seat, (until the next station is
reached, where there is a supply of thimble-
25 seals and the lock can again be resealed,) a
wire 17 (shown in broken lines in Fig. I) is
then passed through the circular hole 18 in
the head of the pin back of said pin and
through the perforate hole 19 in the stem of
30 said pin, and is then fastened around the sta-
ple 5 to hold the locking-pin in its position
until it is resealed.

I claim as my invention—

1. In a seal-lock, the **U**-shaped spring lock-
35 ing-pin, the double prong at the locking end
of said pin, the barbed points on the ends of
said prongs beveled on their under sides and

arranged for engagement within the beveled
recesses in their seats in the seal, and a fran-
gible seal having a single orifice longitudi-
nally thereof, into which said locking end ex-
tends upwardly, so as to enter the seal from
beneath, substantially as and for the purpose
set forth. 40

2. In a seal-lock, a **U**-shaped spring lock-
ing-pin, the double prong at the locking end
of said pin, the beveled grasping barbed points
on the ends of said prongs that fit in the be-
veled recesses in their seats in the seal, the
said locking end extending upwardly to enter 50
the seal from beneath, a thimble-shaped fran-
gible seal in which the key operates, having
an annular recess at the bottom of said seal,
and the anti-picker collar around the stem of
the pin fitting in said recess, substantially as 55
and for the purpose set forth.

3. In a seal-lock, a **U**-shaped spring lock-
ing-pin having a bifurcated operative end ex-
tending upwardly to enter the seal from be-
neath, barbed points on said bifurcated end, 60
the inverted frangible seal provided with a
key-hole running longitudinally with said
seal, and locking-chamber, into which said
key-hole enters, and the annular beveled
shoulder within said seal, into which the 65
barbed points of the locking-pin spring and
effect a lock, and the wire 17, that passes
through the perforations in the key and fast-
ens around the staple 5, substantially as and
for the purposes set forth.

ROBERT W. GILLESPIE.
